(57) **CLAIM**

The ornamental design for a bucket attached to body mass index meters, as shown and described.

DESCRIPTION

1. Bucket attached to body mass index meters

1.1 : Front

1.2 : Left

1.3 : Right

1.4 : Back

1.5 : Top

1.6 : Bottom

1.7 : Perspective

1.8 : Perspective

1.9 : Perspective

1.10 : Perspective

The mass index meter, shown in dotted lines in views 1.9 and 1.10, form no part of the claimed design.
